UNITED STATES PATENT OFFICE.

HENRY C. SISCO, OF ANDERSON, INDIANA, ASSIGNOR OF ONE-HALF TO
H. L. MILLSPAUGH, OF ANDERSON, INDIANA.

SEAL FOR STOP-COCKS.

No. 822,025.

Specification of Letters Patent.

Patented May 29, 1906.

Application filed July 31, 1905. Serial No. 272,060.

To all whom it may concern:

Be it known that I, HENRY C. Sisco, a citizen of the United States, residing at Anderson, in the county of Madison, State of Indiana, have invented certain new and useful Improvements in Seals for Stop-Cocks, of which the following is a specification, reference being had therein to the accompanying drawings.

10 This invention relates to a seal for stop-cocks, and particularly to a cap adapted to fit the head of the stop-cock.

15 The invention has for an object to provide for an improved construction of seal embodying a stirrup adapted to pass at opposite sides of a stop-cock and provided upon its upper face with a cap to fit the head of the cock and prevent any turning or movement thereof after the seal is applied in position without

20 removal of the seal.

Other and further objects of the invention will be hereinafter set forth and the novel features thereof defined in the appended claims.

25 In the drawings, Figure 1 is a perspective of the invention applied to a stop-cock. Fig. 2 is a vertical section on the line 2 2 of Fig. 3. Fig. 3 is a similar view on the line 3 3, Fig. 2; and Fig. 4 is a bottom plan thereof.

30 Like letters of reference refer to like parts throughout the several figures of the drawings.

The letter A shows a stirrup formed of any desirable material, preferably of sheet metal, and provided with a top portion A', having an aperture A² therein to pass over the head B' of the stop-cock B. This top portion is formed at opposite sides with depending portions A³, provided with suitable apertures A⁴, through which a sealing device of any desired character may be passed—such, for instance, as the wire A⁵, having a lead seal A⁶ thereon, said wire passing through the depending portion upon one side beneath the body of the cock and thence through the aperture in the opposite depending portion, where the seal is applied. The top A' of the stirrup is provided with a cap C, formed in any desired manner and attached to said stirrup, for instance, as shown

herein, where a single piece of metal is bent into the rectangular form of the head B' of the stop-cock and provided at each side with a horizontally-extending portion C', projecting beneath the head A' and secured thereto, 55 if desirable, for instance, by means of the in-turned stiffening portion A⁷ to overlap the portion C'. The opposite ends of this cap are folded upon themselves, as shown at C², thus completely inclosing and protecting the 60 head of the stop-cock.

The invention is applied by simply slipping the cap and stirrup over the cock and head and then drawn closely inward to the sides of the cock by means of the wire to which the 65 ordinary seal is applied, which thereby prevents the cock from being turned or otherwise tampered with without removing the seal or injury of the parts which would indicate such tampering. The stirrup extending 70 at each side of the cock will also render tampering with the same impossible and prevent injury thereof, while the form of the parts permits their application to many different sizes of stop-cocks which are in use and 75 permits it to be adjusted closely to the sides thereof, so as to prevent movement or unauthorized tampering with the parts.

Having now described my invention and set forth its merits, what I claim, and desire 80 to secure by Letters Patent, is—

1. A seal for stop-cocks comprising a stirrup provided with angularly-disposed side walls adapted to contact with the cock and having an upwardly-extending angular cap 85 secured to its top portion to embrace the operating-head of said cock.

2. In a stop-cock, a stirrup provided with an aperture in its upper portion, a cap adapted to inclose the head of said cock and provided with lateral flanges disposed beneath said stirrup, and means for securing said stirrup in position.

In testimony whereof I affix my signature in presence of two witnesses.

HENRY C. SISCO.
